United States Patent

Des. 235,860
Patented July 15, 1975

235,860

AUTOMOBILE

Karl Wilfert, Gerlingen-Waldstadt, and Friedrich Geiger,
Böblingen, Germany, assignors to Daimler-Benz
Aktiengesellschaft

Filed Feb. 7, 1973, Ser. No. 330,433

Claims priority, application Germany Aug. 18, 1972

Term of patent 14 years

Int. Cl. D12—08

U.S. Cl. D12—92

FIG. 1

FIG. 2

FIG. 3

FIG. 4

FIG. 1 is a front elevational view of an automobile showing our novel design:

FIG. 2 is a rear elevational view thereof;

FIG. 3 is a left side elevational view thereof; and

FIG. 4 is a top plan view thereof.

The right side of the automobile is substantially the same as the left side shown in FIG. 3.

We claim:

The ornamental design for an automobile, as shown and described.
